FLOOR POLISHER

Joseph Palma, Jr., Berwyn, Ill., assignor to S. C.
Johnson & Son, Inc., Racine, Wis.

Application December 8, 1949, Serial No. 6,510

Term of patent 14 years

(Cl. D9—2)

To all whom it may concern:

Be it known that I, Joseph Palma, Jr., a citizen of the United States residing at Berwyn, in the county of Cook and State of Illinois, have invented a new, original, and ornamental Design for a Floor Polisher, of which the following is a specification, reference being had to the accompanying drawing, forming part thereof.

Fig. 1 is a side perspective view of a floor polisher, showing my new design.

Fig. 2 is a top plan view thereof with the handle omitted for convenience of illustration; and

Fig. 3 is a side elevational view of Fig. 2.

The side not shown is substantially the same as the one shown in Figure 1.

The dominant features of my design reside in the portions shown in full lines.

I claim:

The ornamental design for a floor polisher, as shown and described.

JOSEPH PALMA, JR.
